CLAIM

The ornamental design for a set of vice blocks, as shown and described.

DESCRIPTION

FIG. 1 is a side elevational view of the design for a set of vice blocks with the broken lines representing the environment in which the vice blocks are utilized;

FIG. 2 is a perspective view of the lower right hand vice block shown in FIG. 1;

FIG. 3 is a side elevational view of the design shown in FIG. 2;

FIG. 4 is a front elevational view of the design shown in FIG. 3;

FIG. 5 is a rear elevational view of the design shown in FIG. 4;

FIG. 6 is a top plan view of the design shown in FIG. 3;

FIG. 7 is a bottom plan view of the design shown in FIG. 3;

FIG. 8 is a perspective view of the upper left hand block shown in FIG. 1;

FIG. 9 is a side elevational view of the design shown in FIG. 8;

FIG. 10 is a left end elevational view of the design shown in FIG. 9;

FIG. 11 is a right end elevational view of the design shown in FIG. 9;

FIG. 12 is a top plan view of the design shown in FIG. 9; and

FIG. 13 is a bottom plan view of the design shown in FIG. 9.
